VALVE RECEIVING LINE CLAMP

John W. Mullins, P.O. Box 20524,
Oklahoma City, Okla. 73120

Filed Feb. 19, 1974, Ser. No. 443,896

Term of patent 14 years

Int. Cl. D23—01

U.S. Cl. D23—40

FIG. 1

FIG. 3

FIG. 5

FIG. 6

FIG. 2

FIG. 4

FIG. 7

FIG. 8

FIG. 1 is a perspective view of a valve receiving line clamp showing my new design;

FIG. 2 is a perspective view inverted from the position of FIG. 1;

FIG. 3 is a side elevational view of FIG. 1;

FIG. 4 is a side elevational view of the opposite side of the view shown in FIG. 3;

FIG. 5 is a right end elevational view of FIG. 3;

FIG. 6 is a left end elevational view of FIG. 3;

FIG. 7 is a top view of FIG. 5; and,

FIG. 8 is a bottom view of FIG. 5.

The dotted line representation of a valve and line of FIGS. 1 and 3 are for the purpose of illustration only.

I claim:

The ornamental design for a valve receiving line clamp, substantially as shown and described.
